UNITED STATES PATENT OFFICE.

SIDNEY JOB POCOCK, OF ESHER, ENGLAND.

CHILD'S COMBINED ROTARY CHAIR AND PLAY-TABLE.

1,313,330.

Specification of Letters Patent.

Patented Aug. 19, 1919.

Application filed July 5, 1917. Serial No. 178,729.

To all whom it may concern:

Be it known that I, SIDNEY JOB POCOCK, a subject of the King of Great Britain and Ireland, and resident of Esher, county of 5 Surrey, England, have invented a certain new and useful Improvement in Children's Combined Rotary Chairs and Play-Tables, of which the following is a specification.

This invention relates to a child's combined chair and play table, and consists essentially of a base, a chair rotatably mounted on said base and a play table, which table may, according to one arrangement, be fixed to the base, the chair being rotatable 15 in a central opening in said table, or said table may be suitably secured to said chair so as to rotate therewith.

The invention is illustrated by the accompanying sheets of drawings. Of the drawings:

Figure 1 is a plan view of the combined device with stationary play table and rotatable chair.

Fig. 2 is an elevation of said combined device, partly in section.

Fig. 3 is a detail view showing how the pillars which support the table detachably interlock with the latter and also with the base.

Like letters of reference indicate corresponding parts in the several figures.

In carrying out the invention, and dealing first with the arrangement shown in Figs. 1 and 2, there is provided a circular 35 base *a* mounted on roller or ball casters *b*, said base *a* on its upper or tread surface *c* being provided with radiating ribs *d*. At a suitable height above said base, *a* and carried by pillars *e* mounted on the base is 40 the play table proper, said table consisting of a wide annulus or flat ring *f* provided on its outer periphery with a suitable guard rail or fence *g*, and on its inner periphery with an upstanding bead *h*, said guard rail or 45 fence *g* and bead *h* serving to prevent toys

placed on said table from being pushed from off the same, the diameter of the central opening *i* being such as to allow of the free rotation of the chair *j* therein on the child pushing against the ribs *d* on the base *a*, 50 or against the tread surfaces *c* thereof.

The chair *j* is centrally and rotatably mounted on the base *a*, a preferred arrangement being a central vertical pillar *k* on the top of which the chair is detachably 55 mounted in any suitable manner.

The play table *f* and its guard rail or fence *g* is made in halves, hingedly connected together as at *m* so as to fold up when detached from the supporting pillars which 60 screw into both table and base, and further, the chair supporting pillar may be detachably fixed so as to be readily dismantled for packing or storage purposes.

The combined article may be made wholly 65 of wood, or partly of wood and metal, or in any suitable material, and the constructional details may be varied without departing from the spirit of the invention.

Having now described my invention, what 70 I claim as new and desire to secure by Letters Patent of the United States is:—

A child's collapsible rotary chair and play table device comprising in combination, a base, a plurality of radially disposed traction ribs thereon, a two-part annular table hingedly connected together, inner and outer rims for the table, pillars for detachably securing the base and table together, a central stationary chair supporting post, a chair detachably mounted in said post and having a back extending above the inner rim of the 75 table.

In testimony whereof I have affixed my signature in presence of two witnesses.

SIDNEY JOB POCOCK.

Witnesses:

BENJ. THOS. KING,
ROBT. HUNTER.
